TAYLOR BLOW, OF ST. LOUIS, MISSOURI.

Design No. 3,361, dated February 9, 1869.

DESIGN FOR A TRADE-MARK

The Schedule referred to in these Letters Patent and making part of the same.

To whom it may concern:

Be it known that I, TAYLOR BLOW, of St. Louis, in the county of St. Louis, and State of Missouri, have invented or produced a new and original Design for a Trade-Mark; and I hereby declare the following to be a full, clear, and exact description of the same, reference being had to the accompanying drawing.

The design in question, of a long barrel, or a Bourbon-whiskey barrel, is represented in perspective, so as to show one end, upon which appear the words "Old Long-Barrel Bourbon Whiskey, T. B.", as seen in the drawing, the whole design constituting a brand, or

trade-mark, intended to be applied to a barrel or other vessel or cask containing the whiskey named.

What I claim, and desire to secure by Letters Patent, is—

The design for a trade-mark herein shown and described.

In testimony whereof, I have signed my name to this specification, before two subscribing witnesses.

TAYLOR BLOW.

Witnesses:

C. F. MILLER,
JOHN H. SIMPSON.
